ADJUSTABLE HANDLE FOR TOOTHBRUSHES

Ferdinand Robert Haupt, St. Paul, Minn.

Application April 28, 1947, Serial No. 744,421

1 Claim. (Cl. 306—6)

2

This invention relates to new and useful improvements in toothbrushes. In particular, it is concerned with toothbrushes of the adjustable type, having relatively movable brush and handle portions, with the backs of each lying in substantially the same plane.

In my novel toothbrush, the brush or head portion and the handle portion being substantially and smoothly in the same plane provides a compact and streamlined structure fully equivalent to that of any non-adjustable brush now known to me. My brush has the additional advantage of being fully and easily adjustable, over a wide angle and within the common plane of head and handle thereof, so that proper care of all surfaces of the teeth may be effected. Furthermore, the adjustment mechanism is concealed, i. e., is self-contained within the interior of the toothbrush. The application of required torque between head and handle, as by mere finger pressure, will change the relative angle therebetween; yet the adjustment is sufficiently stable, when once made, to prevent any changes by forces exerted during normal use of the toothbrush for its intended purpose.

The invention will be more readily understood by reference to the accompanying drawing, in which:

Figure 1 is a fragmentary perspective view of one form of my improved toothbrush,

Figure 2 is a vertical section of a part of the brush on the line S—S, Figure 1, and

Figure 2A is a bottom plan view of a portion of the brush-head.

Similar numerals refer to similar parts throughout the several views.

In Figure 1, handle 10, terminating in semi-circular portion 11, and brush-head 12, terminating in cooperating semi-circular portion 13, are in the same plane and in adjustable relationship therein about the central axis of semi-circular portions 11 and 13. The brush-head carries clumps of bristles 14, cemented or otherwise anchored in suitably spaced holes 15. Handle 10 and head 12 are permanently but movably held together by hollow rivet 16 and solid rivet 17.

As shown in Figure 2, the combination of hollow rivet 18, solid rivet 17 having its stem internally located therein, and coiled compression spring 19 placed around the shank and beneath the head of hollow rivet 18, holds semi-circular portion 13 of brush-head 12 firmly pressed against cooperating semi-circular portion 11 of handle 10. The internal or cooperating faces of circular portions 11 and 13 contain

respectively radial depressions 19' and cooperating radial protrusions 20, equally spaced, e. g., as shown in Figure 2A, and preferably of rounded or semi-circular cross-section. The shank of solid rivet 17 fits tightly within hollow rivet 18, and its exposed tip may additionally be peened over or otherwise secured so as to hold the assembly firmly together.

With the arrangement shown in Figures 1 and 2, it will be apparent that the brush-head 12 may be moved sidewise in either direction with respect to the handle 10, about the axis of the rivet 17, and furthermore that it will be quite rigidly held in any one of the several possible positions defined by cooperating protrusions 20 and depressions 19', by means of compression spring 19.

In place of rivets, other means for holding handle and brush-head portions in assembled relationship may be employed. For example, screws or bolts may be used, in which event the head may readily be removed and replaced.

Other means of locking the head in the desired angular position may also be employed.

It will be apparent that, although the brush-head 12 is in the same plane as the forward portion of the handle, particularly the semi-circular portion thereof, and in effect forms an extension thereof, the rearward portion of the handle may if desired be in some other plane at an angle with the plane of the forward portion.

The adjustable feature of my novel toothbrush provides distinct advantages when employed with brush-heads having the conventional uniform arrangement of bristles, and in which the clumps of bristles may be restricted to any desired area of the face of the brush-head, or may be spaced over the entire face including the semi-circular portion. A further distinct improvement is obtained by the combination including an arrangement of bristles as indicated in Figures 1 and 2, wherein the bristles in effect form a wedge with the peak of the wedge above the longitudinal axis of the brush-head and inclined upwardly from the juncture of head and handle. With this arrangement of bristles, and with the brush-head at a sharp angle with the handle, proper care of the teeth is greatly facilitated, since the peak of the wedge may then readily be placed directly in line with the vertical spaces between adjacent teeth.

What I claim is as follows:

In an adjustable toothbrush, an adjustable head and handle comprising: a handle having at one end a flat semi-circular axially perforated

hinge portion having an interior face and an exterior face; and, as an angularly adjustable extension thereof, a brush-head having, at the end adjacent the handle, a flat semi-circular axially perforated hinge portion having an interior face and an exterior face; one of said interior faces having equally spaced radial depressions and the other having cooperating equally spaced radial protrusions fitting within said depressions; the axial perforations of one of said joint portions terminating at the exterior face in an enlarged recess; a compression coil spring fitting within said enlarged recess; a hollow rivet passing through the axial perforations of said hinge portions and passing through said coil spring, and having a flat head fitting within said enlarged recess and over said spring, holding said spring under compression, and holding the said hinge portions in adjustable co-operating relationship with the two interior faces together; and a solid rivet with its stem fitting tightly within the axial bore of said hollow rivet, said solid rivet retaining said hollow rivet in place against the pressure of said compression spring.
